UNITED STATES PATENT OFFICE.

THOMAS L. GREEN, OF INDIANAPOLIS, INDIANA.

DESIGN FOR A CAKE-CUTTER.

SPECIFICATION forming part of Design No. 24,077, dated March 5, 1895.

Application filed January 2, 1895. Serial No. 533,661. Term of patent 3½ years.

To all whom it may concern:

Be it known that I, THOMAS L. GREEN, a citizen of the United States, residing at Indianapolis, in the county of Marion and State of Indiana, have invented and produced a certain new and original Design for a Cracker and Cake Cutter or Similar Article, of which the following is a specification, reference being had to the accompanying drawings, showing a plan and a side view of the cutter to cut crackers and cakes or similar articles of my design.

Figure 1, is a plan view of the cutting edges, showing my design. Fig. 2, is a side view of same, these two views being deemed necessary to fully illustrate my design.

The leading features of my design consist in a cutter for crackers and cakes or similar articles, the outlines of which when viewed from the cutting edges as in Fig. 1, are in the

form or shape of a medallion, in which the leading features thereof are the scalloped short sides thereof C. D. substantially as shown, and the long sides of the cutter having the arc of a circle or a large scallop as shown 25 at A and B in the center of said sides, and connected to the scallops on the ends by means of the depressed parallel lines E. and E'.

Having thus described the nature and object of my design, what I claim as new, and 30 desire to secure by Design Letters Patent, is—

The design for a cracker and cake cutter or similar article, substantially as herein shown and described.

In testimony whereof I affix my signature 35 in presence of two witnesses.

THOMAS L. GREEN.
